UNITED STATES PATENT OFFICE.

ALEXANDER S. NICOL, OF ABERDEEN, WASHINGTON.

COMBINED WET AND DRY PIPE VALVE.

No. 886,629.

Specification of Letters Patent.

Patented May 5, 1908.

Application filed August 9, 1906. Serial No. 329,868.

To all whom it may concern:

Be it known that I, ALEXANDER S. NICOL, residing at Aberdeen, in the county of Chehalis and State of Washington, have invented 5 a new and Improved Combined Wet and Dry Pipe Valve, of which the following is a specification.

This invention, in its general nature, relates to improvements in automatic sprinkler 10 systems for buildings, and it primarily has for its object to provide an improved type of automatic valve mechanism which will automatically actuate an alarm when water passes through the same, and which is adapt- 15 ed for use on either the wet or dry pipe plan.

Heretofore, so far as I know, it has been the practice, when using the wet and dry 20 plan sprinkling systems, to accomplish the desired results, two separate valve mechan- 25 isms have been employed, requiring special adjustment for setting the system to operate on either the wet or dry plan.

Generically, my invention comprehends a 30 single complete mechanism in which a plu- 25 rality of valves are co-operatively combined and so arranged that when used on the dry pipe plan a predetermined water pressure in one direction will be held in check by a lower air pressure against the controlling valve and 35 when used on the wet pipe plan, any circulation of water through the controlling valve will set in operation the alarm mechanism.

In its more complete nature, my invention 40 embodies a single valve casing, having air inlets, a plurality of valves mounted in said casing, counterbalanced trip mechanism for holding the valves to a normal position, and closure devices for closing said air inlets when the trip mechanism is automatically released 45 by the automatic opening of the controlling valves within the casing.

In its more subordinate features, my invention consists in certain details of construction and peculiar combination of parts, all of 45 which will hereinafter be fully described, pointed out in the appended claims and illustrated in the accompanying drawings, in which:—

Figure 1, is a perspective view of my im- 50 proved construction of valve mechanism. Fig. 2, is a vertical section of the same showing the valve mechanism adjusted to a closed position with the air pressure on, the equipment being of the dry pipe plan. Fig. 55 3, is a similar view, the main controlling valves being open, the supplemental valves

for closing off the air inlets to the casing, the parts being in position to provide for actuating the alarm. Fig. 4, is a vertical section of my improved valve mechanism showing 60 the same as set for a wet pipe equipment. Fig. 5, is a similar view showing the parts in position for actuating the alarm mechanism when used for a wet pipe equipment. Fig. 6, is a detail view of the main valve and the trip 65 controlled adjusting devices that coact therewith. Fig. 7, is a sectional view of a slightly modified construction of my valve mechanism hereinafter specifically referred to.

In the practical application of my invention, I provide a single valve casing A, preferably formed of three sections 1, 2 and 3, each provided with suitably arranged man- 70 hole and closure therefor, designated 10, 20, 30 to provide for the removal of the valves 75 for setting my mechanism for operative use on either wet or dry pipe equipments or for removing all or either of the several valves for adjusting or replacing their packing 80 rings.

One of the casing sections designated 1, forms the inlet end, as the same joins with the water supply pipe S and the one designated 3 connects with the outlet or offtake pipe O as clearly shown in Figs. 1 and 2. 85

Each of the casing sections has a valve seat, the several seats being designated a' b' and c' and with each of the seats engage the several valves a, b and c, the seats a' and c' being preferably knife edge seats to engage 90 with the packing or bearing rings a² and c² of the valves a and c.

The valve b which is located in the intermediate casing section 2, is also provided with a packing ring b² to engage with the wide seat b' which, as is clearly illustrated in Figs. 4 and 5, has an annular groove b³ that communicates with an outlet 4 through the casing section 2 with which connects a valved pipe 5, in practice, suitably connected with 100 an alarm mechanism (not shown) arranged to be actuated by a water jet passing through the pipe 5, as will hereinafter more fully appear.

The valve casing A, at a point in alinement 105 with the stem 6 of the valve a, has an air port 60 in the shape of a tapering opening through which the valve stem 6 passes and which, when the valve a is shifted to its open position, is automatically closed by a tapering 110 plug or supplemental valve 61 mounted on the stem 6, as shown, and the said casing, at a

point in alignment with a stem 7 that coacts with the valve *c* has a similar air inlet 70, which, when the valve *c* is opened, is automatically closed by the plug or supplemental 5 valve 71 on the stem 7.

At a point intermediate the valves *a* and *c*, the casing has an outlet 8 that opens into a valved offtake pipe 80 which in practice leads to a suitable alarm mechanism (not 10 shown) arranged to be set in operation by a water stream passing through the pipe 80, and at a point above the valve *c* the casing has a valved drain pipe 9.

When my invention is utilized in a dry 15 pipe equipment, the valve *b* has no special function, and in practice, is preferably removed from the valve casing to reduce friction on the water flowing through the casing.

When the parts are at their normal position 20 as in Fig. 2, the valve *a* is held to its seat by hold back devices, which, when set, are held to their adjusted positions by the closure of the outlet valve *c*, which is held down to its seat by the air pressure on top of it, which 25 may be and preferably is, less than the water pressure on the valve inlet *a*, and but slightly in excess of the atmospheric pressure in the valve casing between the valves *a* and *c*, which is provided for by the air inlets 60 30 and 70 before referred to.

The locking devices before referred to consist of the stem 7 which extends through the casing and presses down on a trigger 10 pivotally mounted on the outside of the casing, 35 which has a lock notch 11 for engaging the latch lever 12 pivoted to the bracket piece 13 on the casing and which carries an adjustable screw bearing 14 that normally engages the outer end of the stem of valve *a*.

40 Combined with the trigger 10^a is a weighted lever 16 pivotally mounted on the casing on whose outer end is adjustably mounted a counterpoise 17 and whose inner end engages the under side of the outer end of the trigger 10^a, as clearly shown in Fig. 2.

The object of the weighted lever 16 is that in case the water pressure forward of the valve *a* should be a low pressure, there would be a liability of accidental water column 50 forming and holding valve *c* down on its seat, which would prevent the opening of valve *a*.

By providing the weighted lever, the weight thereon can be so adjusted that it will 55 lift a column of water 20 feet (more or less) high above the valve *c*, it being understood that proper allowance would be provided for for the assistance the lever would receive from the water pressure at the inlet end of the valve casing.

60 It will be noticed the stem or member 7 is not rigidly connected to the valve *c* but is composed of two pivotally connected portions, the upper one of which is connected to the other above the vent closing valve, and 65 the said upper member is arranged to engage

a seat or bearing on the under side of valve *c* when the latter is closed and the valve *c* is hinged to a link member 18 in turn pivotally connected to the inside of the casing section 3, so that the valve can be opened 70 back flatwise and thereby reduce frictional resistance on the water flowing past the said valve.

When my invention is used on the dry pipe plan, a suitable amount of priming water is 75 sustained above the valve *c*, in practice, about four or five inches in depth, and this water acts as a cushion between the air and valve *c*.

The drain pipe above valve *c* is normally 80 shut off and is used only when it is desired to draw the water from the pipes when changing my valve mechanism from a wet to a dry plan, and in practice, a cut off gate (not 85 shown) is provided in the feed or inlet pipe for shutting off the water supply when it is desired to gain access to valve *a* or to apply or remove casing A.

The parts being arranged as shown in Fig. 2, by reason of the construction and combination thereof as described, when air pressure above valve *c* is reduced, the said valve instantly rises through the counterpoise action and the water pressure which now opens valve *a* and passes up against valve *c*, it being understood 90 that the opening of the valves *a* and *c*, effects the instantaneous closure of the air inlets to the casing, it being also understood that after starting the stem 7 and the valve *c* up, the lever 16 slips from the trigger 10^a and 100 thus permits the latch lever that holds the valve *a* to drop down and release valve *a* to permit it freely moving back to the position shown in Fig. 3, which shows the position of the parts when the water flows through the 105 valve casing and into the offtake pipe that leads to the alarm mechanism.

When my invention is utilized in a wet pipe system, the valve *c* is dispensed with and the valve *b* is mounted over its seat, as 110 clearly shown in Fig. 4, by reference to which it will be noticed that when the system pipes and the valve casing have the main or feed pipe pressure, pressure on each side of valve *b* is equalized and the said valve, by gravitation, closes off the outlet channel *b'* to the offtake connected therewith, it being understood that when my valve mechanism is utilized in the wet pipe system, the locking devices are inert, and the valve *a* is normally 115 forced back to cause the plug valve on its stem to close the air inlet 60, the other inlet 70 being now similarly closed by the fluid pressure against the plug valve in stem 7.

Now, when the parts are assembled, as in 120 Fig. 4, a reduction of the water pressure above valve *b* at once provides for circulation of water past the valve *b* and in consequence a portion of the water passes off 125 through channel *b'* to the offtake in com- 130

munication therewith for actuating an alarm or signaling mechanism.

While I prefer to arrange the valve *b*' within the casing *A* between valves *a* and *c*, 5 I do not limit myself to such coöperative relation of the valves *a*, *b* and *c* since valve *b* may be located at any suitable point in the distributing pipes, either above valve *c* or in advance of valve *a*, for example, as shown 10 in Fig. 7.

From the foregoing description, taken in connection with the accompanying drawings, it is believed the complete construction, the 15 operation and the advantages of my invention will be readily apparent to those skilled in the art to which it appertains.

Having thus described my invention, what I claim and desire to secure by Letters Patent, is:—

20 1. The combination in a valve mechanism of the character described, with the casing, the sliding inlet controlling valve, the hinged outlet valve and the valved offtake connected with the casing between the inlet 25 and outlet valves, said casing having air inlets; of means for positively holding the inlet valve to its closed position, means controlled by the valves for closing the air inlets at predetermined times, and trip devices 30 controlled by the closure of the outlet valve for releasing the means that holds the inlet valve to its closed position when the outlet valve automatically rises, as set forth.

2. A valve mechanism for the purposes 35 described, comprising a casing, having a pair of valved offtakes intermediate its inlet and outlet ends, a valve for controlling the outlet end, normally closed by fluid pressure above it, a normally closed valve in the casing between the inlet and outlet valves that cuts 40 out one of the valved offtakes; and means for holding the inlet valve closed, said means being held to the valve closing position by

the closure pressure of the outlet valve and adapted to automatically release said inlet 45 valve when the outlet valve opens, as set forth.

3. In a water distributing means of the character described, the combination with the distributing pipe sections; of a valve 50 casing connected thereto, consisting of three sections, a valve detachably mounted in the inlet casing section, a valve detachably mounted in the outlet section, an automatically closed valve detachably mounted in 55 the intermediate section, the outlet valve being normally closed by fluid pressure against it, means for holding the inlet valve normally to its closed position controlled by the closure action of the outlet valve, and a 60 pair of valved offtakes joined with the intermediate casing sections, one of which is normally held closed from the water supply by the valve in the intermediate chamber, all being arranged substantially as shown 65 and described.

4. In a valve mechanism of the character described, the combination with the casing, a check valve in the inlet end having a stem projected through the casing, a hinged valve 70 in the outlet end, a plunger that projects outside the casing and is engaged by the hinged valve when closed, the latter being normally closed by air pressure against it, a pivoted pusher arm that engages the stem of 75 the inlet valve, a latch for holding said arm to its pushing position, said latch being held to its operative position by the plunger engaged by the hinged valve and a counterpoise that engages the outer end of the latch, 80 all being arranged substantially in the manner shown and for the purposes described.
